(21) Appl. No.: **29/551,184**

Primary Examiner — Kevin Rudzinski

(22) Filed: **Jan. 11, 2016**

Assistant Examiner — Kathleen Jones

(51) LOC (10) Cl. **14-04**

(74) *Attorney, Agent, or Firm* — Sterne, Kessler, Goldstein & Fox P.L.L.C.

(52) U.S. Cl.

CLAIM

USPC **D14/488; D14/486**

The ornamental design for a display screen or portion thereof with graphical user interface, as shown and described.

(58) **Field of Classification Search**

DESCRIPTION

USPC **D14/485-495**

The FIGURE is a front view of a display screen or portion thereof with graphical user interface showing the claimed design.

CPC **H04N 7/157; H04L 29/06421**

The outermost broken lines in the FIGURE show a display screen or portion thereof, and form no part of the claimed design. The other broken lines in the FIGURE show portions of the graphical user interface that form no part of the claimed design.

See application file for complete search history.
